UNITED STATES PATENT OFFICE.

CHARLES WERNER, OF CLEVELAND, OHIO.

DESIGN FOR AN ARM FOR LIGHTING-FIXTURES.

51,293.

Specification for Design. Patented Sept. 18, 1917.

Application filed January 12, 1917. Serial No. 142,112. Term of patent 8½ years.

To all whom it may concern:

Be it known that I, CHARLES WERNER, a citizen of the United States, residing at Cleveland, in the county of Cuyahoga and State of Ohio, have invented a new, original, and ornamental Design for an Arm for Lighting-Fixtures, of which the following is a specification, reference being had to the accompanying drawing, forming part thereof.

The figure is a perspective view of an arm for lighting-fixtures, showing my new design.

I claim:

The ornamental design for an arm for lighting-fixtures, as shown.

CHARLES WERNER.
